UNITED STATES PATENT OFFICE.

JAMES B. ALLFREE, OF CUMBERLAND, MARYLAND, ASSIGNOR OF ONE-HALF
TO ROBERT SHRIVER AND HARRISON SWARTZWELDER, BOTH OF SAME
PLACE.

FLOUR-PACKING MACHINE.

SPECIFICATION forming part of Letters Patent No. 359,951, dated March 22, 1887.

Application filed June 1, 1886. Serial No. 203,806. (No model.)

To all whom it may concern:

Be it known that I, JAMES B. ALLFREE, a citizen of the United States, residing at Cumberland, in the county of Alleghany and State 5 of Maryland, have invented new and useful Improvements in Flour-Pack Machines, of which the following is a specification.

This invention relates to certain new and useful improvements in machines for packing 10 flour and similar substances into barrels or other receptacles; and it consists, substantially, in such combinations of parts and details of construction as will hereinafter be distinctly described, and pointed out in the claims.

15 The invention relates more particularly to that class of flour-packer in which are employed a packing-auger and a surrounding packing-tube and a vertically-moving platform upon which the barrel or other receptacle is placed, such platform being so regulated and controlled by suitable mechanism as to gradually recede or descend from the auger as the receptacle is being filled.

20 The objects of the invention are to provide a machine of this character of a construction by which a more perfect result is had than in many former instances, and to render such machine more sensitive and rapid in its operation and of greater economic value and convenience.

30 Referring to the accompanying sheets of drawings, Figure 1 represents a vertical front elevation of a flour-packing machine in which my invention is embodied, and Fig. 2 represents a vertical side elevation thereof. Fig. 3 represents a vertical sectional elevation. Fig. 4 indicates a horizontal sectional view taken on the line $x-x$ of Fig. 1, and Fig. 5 is a similar view taken on the line $y-y$ of Fig. 1.

40 In the drawings, 1 2 3 4 represent the four columns or uprights, which are securely held together by cross-strips $a-a$, and constitute the stationary frame of the machine. At a convenient height or point on the outside of the frame, at its sides, bearings $B B'$, are bolted fast to the posts, in which is placed and held the horizontal shaft C , of sufficient length to project outward at one end far enough to receive and accommodate the brake-wheel D , which 45 is keyed or otherwise secured thereto. This 50 shaft is the prime medium through which the

moving platform is supported, raised, lowered, regulated, or controlled during the process of filling or packing the receptacles. Around the said horizontal shaft C , between the inner 55 sides of the framing, is coiled a spring, D' , of suitable strength and dimensions, one end of which is attached or secured to the shaft, while the other end is held by an adjustable grip-clutch or ratchet and pawl, E , attached by 60 suitable means, e , to the side of the vertical post 4, as shown, by which the spring D' may be wound up and set or held to any desired tension, and the force thus derived applied or imparted to the shaft C , whereby the platform 65 P is automatically raised to its full height and the increasing weight of the receptacle, as it becomes filled with flour, is compensated.

Fixed or secured to the shaft, at or near each end thereof, to the outer side of that portion 70 covered by the spring and inside of the vertical posts, are two grooved sectors, $G G'$, of such diameter that their peripheries will be in line with the axis of the vertical packing-auger shaft F , and of such length and form of periphery as that the receptacle-platform P will be raised to its full height by one-half rotation of the horizontal shaft, and when thus elevated the supporting chains or ropes $b b'$, by which such platform is suspended, will be received into the grooves of their peripheries.

75 The forward ends of the sectors $G G'$ are adapted for the reception of screw-eyes $h h'$, from which the supporting chains or ropes depend, and by which their length is adjusted 80 to cause the platform to hang level and travel freely in its ways or guides without binding. The platform is inclosed all around, except at the front, by sheet-iron or other suitable material, to prevent flour from falling onto the 85 floor and becoming wasted. It is also provided at its sides with strips of wood 5 6, vertically arranged and partly embracing the posts 1 and 2 of the stationary framing. Being suspended by the wire rope or chains $b b'$ on 90 both sides of and parallel to the axis or line of thrust of the packing-shaft F , all tendency to binding or locking of the platform in its guides is entirely overcome, no matter what 95 amount of pressure may be applied, and a 100 prevalent cause of friction and irregular working removed.

At another convenient point on the outside of the frame is bolted securely the clamp-vise J, the same being arranged in such position as that its jaws *j j* shall inclose the rim of the 5 brake-wheel D. This vise is provided with a spring, *d*, near its lower extremity, by which even pressure of the jaws upon the wheel is maintained, and is also provided with a thumb-screw, *g*, for regulating the tension of the 10 spring, and a cam-lever, K, for instantly relieving or applying the pressure of the jaws *j j*, said jaws being supplied or provided with suitable material, *i i*—as leather—to produce the necessary friction without wearing or 15 facing the brake-wheel. The rim of the brake-wheel has its sides turned off smooth, so as to present uniform parallel surfaces to the grasp of the vise. By this device no other friction than that applied to the brake-wheel itself is 20 caused, and the surfaces brought into action to produce the friction being small and the grip correspondingly greater, their action is very uniform and not affected by atmospheric changes, as is the case with all other forms of 25 brakes now used in this connection.

M represents the usual hopper, constructed, preferably, of sheet-iron and of such shape as may be required to conduct from the bin to the packing-tube N the material to be packed 30 into the receptacles. Its lower end terminates in a cast-iron ring, *l*, of proper size to receive the flange of the packing-tube, and is supported by the bracket Q, securely bolted to the frame and formed so as not to interfere 35 with the movements of the sectors G G'. The front, *m*, of this hopper is of cast-iron, and is adapted to be removed for convenience of construction and access to the interior of the hopper when necessary.

40 When it is required to change from one sized package to another, it also becomes necessary to change the packing-auger *n²* and the tube N, to suit the size of package to be filled. To effect this change the flour in the hopper 45 M must be stopped off from the tube, which is usually performed with a slide located above the tube in some convenient place; and when the slide is not in use some means must be employed to close the opening through which 50 such slide is passed or inserted.

The most convenient place to locate the slide *k* is just above the tube and in the tube-ring *l*, a slot, *n*, being provided for the purpose; but the objection to this place is the 55 presence of the vertical packing-auger shaft F, passing through the center of the space, which requires the slide to be cleft to its center with a slot the size of the shaft. In effecting a change of the tube N a quantity of flour 60 spills or escapes through the slot *n*; and to obviate this I pivot to the slide *k* a movable shutter, *p*, the same being pivoted at a point by which it is allowed to be closed after the slide is introduced, and is formed with a slot 65 or notch, *p'*, to enable it to embrace the shaft F when closed. The slide and shutter are preferably made of sheet-iron. It is of course

necessary to provide against escape of flour through the slot *n* while the slide *k* is not in use, and for this purpose I employ a rubber or other flexible band or apron, *n'*, which is located on the inside of the chamber *r* of the hopper M, and is so attached to the front piece, *m*, as to hang before the opening or slot *n* and completely close the same. On introduction 75 of the slide this apron is pressed back or upward, thus allowing insertion thereof, and when the slide is withdrawn the apron automatically descends or returns and closes the opening, thus effectually acting to prevent the 80 escape of flour.

In order to drive the packing-auger *n²* the upper end of its shaft, which is mounted in bearings *t*, is provided with a beveled gear-wheel, T, that receives motion through the 85 beveled pinion T', attached to the horizontal driving-shaft U, which is suitably connected with the power from whence it derives its motion. The bearing *v* of the said driving-shaft is adapted to be supported in the end of a 90 lever, V, which is pivoted or fulcrumed at or near its middle to the front vertical post, 2, of the framing, at right angles to the shaft, and which is so arranged that when that end thereof bearing the pinion T' is raised the wheels will 95 be in gear and the packing-shaft set in motion, and when depressed they will be out of gear and the packing-shaft stopped. Attached to the other end of the lever V is an adjustable screw-eye, *w*, to which is suspended a connecting-rod, *w'*, whose other or lower end is connected to a lever, X, having a handle at its forward end, and which is pivoted at its other end to a rod, Y, extending across the frame of the machine at the rear. The forward end 105 of said lever X moves or travels in a slotted guide, *x*, attached to the front vertical post, 2, which is provided near the base or bottom of the slot with a suitable notch or catch, *x³*, into which the lever is set when it is desired 110 to put the beveled wheels T T' into gear for starting the packing-auger. On the side of the platform P, contiguous to the lever X, is attached vertically a rod, *y*, carrying an adjustable finger, *y'*, which is shaped and set so 115 as to be capable of pushing the said lever out of its catch, whereupon the pinion T' will drop out of gear automatically by reason of its weight, which largely overbalances the other parts attached to the lever V, and the packing-auger is instantly stopped.

The machine described is what is known as a "right-hand packer," the attachments for connecting and disconnecting the power being at the right-hand side of the frame. In order 125 to convert it into a "left-hand" machine, the lever V, carrying the driving-shaft, is pivoted to the left-hand post and the connecting-rod *w'* is attached at its lower end to an arm, *W''*, fixed to the rod Y, through which it is actuated 130 by the lever X, a suitable guide and trip being provided on the upright 1.

For enabling the packing-tubes to be changed quickly, I employ a cleft rim or flange, *a⁶*, to

which are attached lugs a^1 , adapted to receive a tightening-screw, a^2 . This flange is of such diameter and length as to conveniently fit the ring l of the hopper M while the screw is loosened, and to grasp such ring firmly when the screw is tightened.

It will be seen that the platform may be raised or lowered to its extremes with but one-half rotation of the horizontal shaft C ; also, 10 that the spring receives only the strain caused by the half-turn of the shaft, and being made of half-inch steel and having, say, about thirty-three coils, its liability to breakage is very slight; and, further, that the brake exerts no 15 pressure on the bearings of the said horizontal shaft; and, further, that the platform, being practically centrally hung, cannot be made to bind in its guides by any amount of pressure. The friction not under control is thereby 20 reduced to a minimum, and the force or power required for the work to be done is correspondingly reduced, while the life of the machine is prolonged.

The brake-wheel D is provided with a safety-pin, O^4 , which is designed to come in contact with a rubber bumper, Q^4 , should the brake J fail to operate, and thus save the spring, as the brake-wheel can only move a half-turn.

30 The bearing for the upper end of the auger-shaft is of a construction—that is to say, a gimbal-joint—as shown, by which such shaft is permitted to have a universality of movement; or, in other words, the said shaft is permitted to have a slight rocking movement in addition to its freedom to revolve, this being desirable for the purpose of ease of operation thereof in the packing process, the said bearing being held against upward thrust by a 35 brace-rod, k^4 , as shown.

40 The bearing of the drive-shaft is constituted of a sleeve, as shown, attached in any suitable manner to its supporting-lever; and it is evident that the shaft is permitted a free and 45 uninterrupted movement in its action, the said lever being at right angles to the said shaft.

Having thus described my invention, what I claim as new, and desire to secure by Letters 50 Patent, is—

1. In a flour-packer, the combination, with the horizontal shaft, the spring D , and brake-wheel, of a pair of jaws pivoted together and attached to the supporting-frame, the same 55 embracing the rim of the brake-wheel, a pressure-spring for said jaws, and an adjusting-screw, and a cam hand-lever, whereby the pressure may be instantly applied or relieved, substantially as described.

60 2. In a flour-packer, the combination, with the slide k , cleft or slotted to its center, of a shutter adapted to be closed over the slot for preventing the escape of flour while the packing-tubes are being changed, substantially as 65 described.

3. The combination, with the horizontal

shaft C and means for controlling the same, of the moving platform and supporting chains or ropes and the sectors $G G'$, arranged upon the shaft near each end, and to which the supporting-chains are adjustably suspended, the said sectors being so constructed on their peripheries as to receive the chains upon elevation of the platform, substantially as described.

70 4. In a flour-packer, the combination, with the horizontal shaft, the spring D' , and brake-wheel provided with pin O^4 , of a pair of pivoted jaws embracing the wheel and provided with buffer Q^4 , a pressure-spring for said jaws, 80 and an adjusting-screw, and a cam hand-lever for instantly applying or relieving the pressure, substantially as described.

5. In a flour-packer, the sectors secured to the horizontal shaft, whereby the moving platform is raised or lowered by means of the suspending chains or ropes, in combination with the said shaft and platform, substantially as described.

85 6. In a flour-packer of the character described, the combination, with the brake-wheel, of frictional gripping-jaws pivoted together and secured to the main frame of the machine, the pressure-spring between the arms of the jaws, the adjusting-screw, and the cam-lever, 90 substantially as described.

95 7. The combination, in a flour-packer having a vertically-moving platform suspended by ropes or chains from sectors keyed on a horizontal shaft, of a spring coiled around this 100 shaft between its end bearings in the main frame and having one end attached to said shaft and the other end attached to an adjustable grip-clutch secured to the frame, substantially as described.

105 8. The combination of the vertically-moving platform, the suspension chains or ropes thereof, the sectors keyed on a horizontal shaft and having chains or ropes secured to their periphery in the plane of the axis of the auger-shaft, the spring coiled on said horizontal shaft and made adjustable, as described, a brake-wheel, and a friction-brake, substantially as described.

110 9. The combination, in a flour-packer, of the stationary frame, the movable platform, the horizontal shaft bearing sectors, to which this platform is flexibly attached, the coiled spring secured to the said shaft and adapted to receive tension by twisting its coils, means for 115 adjusting and maintaining this tension, a friction-brake, and a brake-wheel provided with a stop-pin adapted to be arrested by a cushion, Q^4 , substantially as described.

120 10. The combination, in a flour-packer, with the hopper having a depending ring, of the packing-tube having a cleft rim provided with lugs and an adjusting-screw, a horizontal cleft slide, and a shutter for closing the cleft or slot therein, substantially as described.

130 11. In a flour-packer, the combination, with the auger-shaft having a beveled gear thereto,

of a driving-shaft bearing a beveled pinion adapted to engage said gear, a vertically-vibrating journal for said shaft applied to a lever having its fulcrum in the main frame, a 5 rod connecting one arm of said lever to a hand-lever and adjustably applied to the former lever, and a retaining device for the hand-lever, substantially as described.

12. The combination, with the journal *u* of shaft *U*, the vertically-vibrating lever *V*, the hand-lever *x*, and connecting-rod *w*, of the slotted guide, the platform *P*, and the vertical rod *y*, carrying an adjustable finger, *y'*, all combined and adapted to operate substantially in the manner and for the purposes described.

13. In a flour-packer, a vertically-movable guided platform suspended from sectors, which are keyed on a horizontal spring-actuated 20 shaft, in combination with a packing device

inclosed in a tube, the vertical axis of which coincides with a vertical plane intersecting the perimeters of said sectors, substantially as described.

14. In a flour-packer, a vertically-movable 25 guided platform open in front and closed at the sides and back, in combination with suspension-chains arranged in a vertical plane coinciding with the vertical plane of the axis of the packing-tube, an auger-shaft hung from 30 a gimbal, the driving-gear for this shaft, and a shaft, *C*, bearing sectors, and an adjustable tension-spring, substantially as described.

In testimony whereof I have hereunto set my hand in the presence of two subscribing witnesses.

JAMES B. ALLFREE.
